UNITED STATES PATENT OFFICE.

JOHN DU BOIS, OF WILLIAMSPORT, PENNSYLVANIA.

IMPROVED DREDGING-MACHINE.

Specification forming part of Letters Patent No. **81,076**, dated August 18, 1864.

To all whom it may concern:

Be it known that I, JOHN DU BOIS, of Williamsport, in the county of Lycoming, in the State of Pennsylvania, have invented certain new and useful Improvements in Dredging-Machines and the Manner of Loading and Unloading Mud-Scows; and the following is a full, clear, and exact description of the same, reference being had to the accompanying drawings, making a part of this specification, in which—

Plate I, Figure 1 represents a side elevation of the hull of a dredging-scow with the improved machinery for dredging, connected also to the mud-scow, and the feed-chain way with all of the attachments ready for use. Fig. 2 shows a front end view of the scow and the adjustable vertical frame on which the endless chain is worked to dig and elevate the mud and gravel. Fig. 3 is an end view of the track-frame with the apparatus for raising or forcing down the props attached to the railroad on the deck of the mud-scow, to sustain the weight running over the same. Fig. 4 shows an end sectional view of the mud-scow with the apparatus for loosening the hinged sides to let the mud out. Figs. 5 and 6 show end views of the grouser-boats, with a broken section in Fig. 5, showing the apparatus for raising or forcing down the grousers; also their connecting-frame timbers in broken-off sections. Plate II represents the plan or top view of the dredging-scow with its machinery complete as attached to the mud-scow, the feed-chain guides, and the grouser-boats with their connecting-timbers.

The object of my invention is to furnish a dredging-machine that will do the labor at less cost and at much greater speed, and with perfect uniformity to any desired depth, which cannot be done conveniently or with any certainty by the machines now in use, which require to be held securely in one position, with its grousers at the place where it is used, and while in use, it being operated with a long swinging arm, on the end of which is attached the scoop for taking out the mud and earth and depositing it on a scow or any desired place within its reach, rendering it slow and difficult in its operation, and not well calculated for dredging to a uniform depth, while, on the contrary, my machine is not anchored to any given spot, but when adjusted to dredge

to a given depth it moves at a regular speed, according to the depth it is cutting, the whole length of the feed-chain and the platform by which it is guided, which may be made to any length desired. At each end of the platform is attached a grouser-boat with a feed-chain attached, and extending from boat to boat, the grouser-boats being of sufficient length to make any given number of changes before drawing the grousers.

To enable others to construct my new apparatus and machine, and to readily understand my new process of operation for dredging with it, I will describe it more in detail, referring to the drawings, and to the letters marked thereon.

The same letters indicate the like parts in all of the figures.

I make the hull or scow A in the usual form for such purposes and of the required dimensions for erecting and supporting the necessary mechanism for digging, raising, and depositing the mud or earth on a mud-scow, B, prepared for the purpose, which makes one of the essential parts of my apparatus for dredging.

The boilers, steam-engine, and other machinery for working the whole apparatus (which is not necessary to be shown in the drawings) I place in the bottom of the boat or scow A in such a position as to balance the machinery for digging, raising, and removing the earth or other substance.

In one end of the scow A is an opening, F, of sufficient width and depth for the digging and raising mechanism, which is constructed and operated in the following manner: On both sides of the opening E, I erect two frames, D D, of a sufficient height to give room for the working of the sliding frame E to any desired depth, the two frames, D D, being made strong and firm by caps or plate-timbers a a on their tops, and may also be braced fore and aft, so as to give them any required strength. The frame E is fitted to slide in the frames D D down through the opening F, and is provided with one or more vertical rack-bars, c c, on each side, with ratchets f f, connected to rock-shafts e e, which are coupled together by a connecting-rod, g, so as to be operated by one lever, h, for lowering the frame E and gaging the digging apparatus to any desired depth.

The digging and elevating apparatus consists of two endless chains, C C, passing over and under pulleys H H, on which chains C C are secured a series of two or more scoops or buckets, G, and also hooked prongs i i i, placed in advance of each bucket, so as to break or loosen up the mud or earth before the scoop takes hold of it to lift it out of the water.

The motion and power for working the dredging apparatus above described is communicated by an endless chain-belt, I, fitted to and working upon notched pulleys K K on the shaft J and the driving-shaft L, to which the power is communicated from the engine underneath, the shaft L being supported in a frame, M, on the deck of the boat A.

On the front face side of the vertical frame-timber D are two substantial timbers, N N, framed in so as to extend out horizontally over the whole length of the mud-scow B, they being supported by long braces m, extending from the farther portion of the horizontal timbers N to the top of the vertical post of the frame D and brace-timbers n to the foot of the frame M on both sides.

On the outside of the braces m n are stay-rods of iron k, passing through the loops or staples l l at or near the top of the frames D, they being firmly secured by bolts o o in the loops at their ends. On the long timbers N are iron rails P P, which form the track for the mud-car O to run on to convey the contents from the dredging apparatus to the various apartments of the mud-scow B after it is deposited in the car O from the scoops G, which are provided with hinged bottoms g', so that when the scoop or buckets G are elevated above the track p, and the car O is run back under the bucket, the cam q trips the hooks b b and lets the bottom g fall down and deposit its contents in the car O, which is also provided with a hinged bottom, P, and hook-catches b' b', on one of which is an arm, s, and roller t, so that when the car is moved out on the track by the action of the chain or rope q', connected with it, to any desired compartment of the mud-scow, when a movable cam, u, on the timber U trips the catches b' b' and drops the contents into the mud-scow B.

The rope or chain q' passes around the rollers r r' on the ear-frame N, and back by the side of the elevator-frame D to the driving-pulleys m', which are so arranged on the frame M M as to be thrown into gear or be driven by friction from a wheel on the driving-shaft L, so that by the holding up of the hand-lever n' the ear O is moved in one direction, and reversed by holding the lever down, and when midway the ear is stopped in such a position as to receive another load from the scoop G. When the ear O returns, the bottom P is closed up by the action of the roller Q on the frame N. As the mud-scow B is being depressed by the weight of the substance deposited on it, the truck-frame N is provided at the corners with four upright posts or timbers, R R, on the tops

of which are racks r r and pinions v v, with ratchet-wheels and pawl-levers w w, which operate both ways, so as to either raise the timbers R or force them down on the top or cross-timbers of the mud-scow B, by which means the rail and ear-frame are supported firmly and the dredging-machine and the mud-scow are kept trim together.

When one mud-scow is filled by the process above described, the timbers R R are raised from bearing on it by the action of the pawl-levers w, and being detached from the dredging-machine, it can be floated away for disposing of its contents and another mud-scow put in its place, so that the work of dredging need not be suspended any longer than the time of changing the loaded scow for an empty one.

The mud-scows are constructed in such a manner as to be easily unloaded or discharged of their contents, they being made with a water-tight hull, S, for buoyancy, and two inclined decks, T T, which form the bottom of the boxes W' to receive the mud from the car, as shown in the sectional end view of Fig. 4, each compartment being provided on both sides with hinged doors W W and sliding bolts V V, which are so arranged and connected together by arms x x on rock-shafts X X above the top edges of the scow that the bolts are all drawn at once and the doors opened by the action of a single lever, Y, and connecting-rods y y at one end of the scow, and by the reverse motion of the lever Y the doors W are all closed and the bolts V shoved into the staples z z, whereby they are all at once firmly secured.

When the mud-scow B is placed in the proper position and secured to the dredging-machine A, all ready for operation, the grouser-boats A' and A', as seen in Figs. 5 and 6, are connected together by a frame-work of timbers, B', they being made firm and stiff by any desired number of braces and counter-braces, D' D', as shown on the plan or top view of the figure on plate II. The string-pieces or parallel longitudinal timbers B' B' may be spliced together, so as to get any desired length and distance for the dredging-machine to perform a section of its work, the grouser-boats A' A' being made with two or more water-tight compartments, x, with a longitudinal vertical space E' E' centrally from one end to the other, it having a series of double grooves, e' e', at intervals corresponding with the width of the channels to be cut by the scoops G of the dredging-machine. In the grooves e' e' pieces of plank f' f' are fitted, so that they can be easily put in or taken out. The spaces between the sides of the opening E' and the two planks f' f' form a square box or mortise, in which the grousers H' H' are held and forced down into the earth or drawn up again by the application of mechanical power constructed and arranged as shown in the broken-out section of Fig. 5, or its equivalent. When the grouser-boats and frame are floated to the place and are got into a proper position, and the grousers

$H' H'$ are firmly driven or set, so that the frame-work is anchored fast, the dredging-machine is then placed at one end, the chain or cable G' put in connection with one of the gang of pulleys g on the end of the main driving-shaft K' on the outside of the boat A , and the required amount of power is applied to move it by the action of the friction-roller L' on the fulcrum end of the lever I' and retained by the rack J' , so that the dredging-machine is moved along by the side of the frame $B' B$ in a direct line as fast as the substance is removed to allow it to progress. When one channel has been cut at any required or the proper depth, it is only necessary to draw the planks $f' f'$, leaving the grousers $H' H'$ standing firmly in their fixed position, and float the grouser-boats and frame-work back one section, and put in the planks $f' f'$ to another set of the grooves $e' e'$, and then bring the dredging-machine back to the first starting-point. Again connect the feeding chain or cable G' and proceed to cut, elevate, and carry off another course of mud or earth, and so continue to repeat the process until you have dredged the section the whole width of the length of the grouser-boats $A' A'$, or made your channel wide enough for all practical purposes.

Two or more sets of the digging apparatus as above described may be arranged on one boat or scow, and a sufficient power applied to work them, so that double or treble the width may be dredged at one and the same time. When a section has been dredged the length of the grouser-boats and the frame-work which connects them together, and the work completed the required depth and width, the grousers are raised and the boats and

frame are moved another section, where they are secured in the same manner, and so on for miles or any required distance, so that a perfectly clean and uniform depth and width of channel is made in much less time and expense than it can be done by any other mode or process known or used.

Having thus fully described my improvement in dredging-machines, mud-scows, and grouser-boats, and the mode of connecting the same, and the process of operation, what I claim as my invention, and desire to secure by Letters Patent, is—

1. The arrangement of the sliding frame E , with its elevators $G G$ and hook-prongs $i i$, substantially as herein described.
2. The adjustable sliding frame E , in combination with the rail-track frame N , for the raising and disposing of the mud, earth, or gravel, as herein specified.
3. The construction and arrangement of the grouser-boats $A' A'$, with their platform-connections, in combination with a dredge-boat or scow, substantially as set forth.
4. The mode by which the dredging-scow A is moved forward and guided while in the act of operation, substantially as set forth.
5. The construction and arrangement of the car-track $P P$, with its adjustable supporting-legs $R R$, in combination with the mud or earth-removing vessel B , as herein described, for the purposes set forth.

In testimony whereof I hereunto subscribe my name in the presence of witnesses.

JOHN DU BOIS.
